UNITED STATES PATENT OFFICE

155,334

DESIGN FOR A BICYCLE HANDLEBAR

Roelof Carel de Boer, Amsterdam,
Netherlands

Application October 30, 1948, Serial No. 149,409

Term of patent 14 years

(Cl. D90--11)

To all whom it may concern:

Be it known that I, Roelof Carel de Boer, a subject of the Queen of the Netherlands, residing at Amsterdam, the Netherlands, have invented a new, original, and ornamental Design for a Bicycle Handlebar, of which the following is a specification, reference being had to the accompanying drawing, forming part thereof.

Said drawing is a perspective view of a bicycle handlebar, showing my new design.

I claim:

The ornamental design for a bicycle handlebar, as shown.

ROELOF CAREL DE BOER.
